CLAIM

The ornamental design for a shoe, as shown and described.

DESCRIPTION

FIG. 1 is a front perspective view of a shoe showing my new design;
FIG. 2 is a side view thereof;

FIG. 3 is a rear perspective view thereof;

FIG. 4 is a front perspective view of a shoe showing an alternative embodiment of my new design;

FIG. 5 is a side view thereof; and,

FIG. 6 is a rear perspective view thereof.

The curved oblique shade lines represent a translucent or transparent appearance. The broken lines depicting the remainder of the shoe form no part of the claimed design.
